UNITED STATES PATENT OFFICE.

WILLIAM VON ELM, OF BROOKLYN, NEW YORK.

DESIGN FOR A MOLD FOR FREEZING FOODS.

Application filed October 8, 1928. Serial No. 28,398. Term of patent 7 years.

To all whom it may concern:

Be it known that I, WILLIAM VON ELM, a citizen of the United States, residing at Brooklyn, in the county of Kings and State of New York, have invented a new, original, and ornamental Design for Molds for Freezing Foods, of which the following is a specification, reference being had to the accompanying drawing, forming part thereof.

Fig. 1 is a perspective view of a freezing mold for foods showing my new design.

Fig. 2 is a side elevation.

Fig. 3 is an end elevation.

I claim—

The ornamental design for a mold for freezing foods, as shown.

WILLIAM VON ELM.
